DESIGN FOR A POWER DRIVEN TOOL UNIT

Leonard L. Timm, Aurora, Ill.

Application December 2, 1937, Serial No. 73,318

Term of patent 14 years

To all whom it may concern:

Be it known that I, Leonard L. Timm, a citizen of the United States, residing in Aurora, in the county of Kane and State of Illinois, have invented a new, original, and ornamental Design for a Power Driven Tool Unit, of which the following is a specification, reference being had to the accompanying drawing, forming a part thereof.

The dominant features of my design reside in the portions shown in full lines.

Figure 1 is a side elevational view of a power driven tool unit, showing my new design, and Figure 2 is a plan view of the same.

I claim:

The ornamental design for a power driven tool unit, as shown and described.

LEONARD L. TIMM.
